METERING FUEL PUMP

William E. Leibing, Los Angeles, Calif.

Application December 1, 1947, Serial No. 789,106

2 Claims. (Cl. 103—161)

1

This invention relates to fuel delivery pumps for use in connection with internal combustion engines of the type employed in automobiles, trucks, buses, aircraft, and marine applications.

It is the principal object of this invention to provide a fuel pump of novel design which functions not only to supply liquid fuel to the engine but also to meter the rate of flow to conform to the exact requirements of the engine under all conditions of operation.

A related object is to eliminate the carburetor and fuel pump as conventionally employed in connection with the internal combustion engines of the manifold induction type and to replace these two units with a single fuel pump unit capable of lifting the liquid fuel from the tank and supplying it to the engine in proper amount during all conditions of engine operation.

Another object of this invention is to provide a pump adapted to deliver fuel into the engine manifold, and having a pressure responsive means in communication with the manifold adapted to control the rate of fuel delivery from the pump.

A further object is to provide a fuel pump of this type which may be positioned at a remote location with respect to the engine if desired, so that the fuel while being metered and pumped is not subjected to the heat of the engine.

Another object is to provide a metering fuel pump which may be economically manufactured in quantity, and which is adaptable to engines of wide variation in capacity.

Another object is to provide a device of this type which delivers fuel at a metered rate into the engine manifold either anterior or posterior of the throttle valve controlling air flow to the engine. Other objects and advantages will appear hereinafter.

In the drawings:

Figure 1 is a diagrammatical side elevation showing a preferred embodiment of my invention, and in which multiple discharge conduits enter the intake manifold at spaced locations.

Figure 2 is a view similar to Figure 1 showing a single discharge conduit entering the intake manifold at a location anterior of the throttle valve.

Figure 3 is a view similar to Figure 2 but showing the discharge conduit entering the manifold at a position posterior of the throttle valve.

Figure 4 is a side elevation of a metering fuel pump embodying my invention.

Figure 5 is a sectional elevation taken substantially on the line 5—5 as shown in Figure 4.

2

Figure 6 is a transverse sectional view partly broken away.

Figure 7 is a sectional elevation taken substantially on the line 7—7 as shown in Figure 6.

Figure 8 is an enlarged sectional view partly broken away showing details of construction of one of the pump units.

Figure 9 is a sectional view of one of the deformable ring elements shown in Figures 6 and 8 as it appears before assembly into one of the pump units.

Referring to the drawings, the pump unit 10 includes a housing 11 provided with an end cap 12 and a closure 13. The end cap 12 is connected to the housing 11 by means of an intermediate spacer 14. The spacer 14 may be connected to the housing flange 15 by means of a series of threaded elements 16. Another series of threaded elements 17 serves to connect the end cap 12 to the spacer 14.

As shown in Figure 5 a non-rotary ring 18 is pivotally connected to the housing 11 by means of the pin 19 secured to the housing 11, and is adapted to be moved laterally within the housing by means of the linkage generally designated 20. A raceway 21 is provided on the inner circumference of the ring 18, and mounted in this raceway are a plurality of roller elements such as the balls 22. A rotary sleeve 23 supported on the roller elements 22 is adapted to turn within the non-rotary ring 18. Mounted within the rotary sleeve 23 is a rotor assembly generally designated 24. The rotor assembly 24 includes a shaft 25 projecting outwardly through the end cap 12 at one end and adapted to rotate within the bearings 26 and 27. The bearing 26 is carried by the end cap 12 and the bearing 27 is mounted within the closure 13.

A keyway 28 is provided in the projecting end 40 of the shaft 25 for connection to any suitable drive means, such as, for example, a flexible drive shaft, a pulley, sprocket or gear. While any of these conventional drive means may be employed for turning the shaft 25, it is to be understood that this shaft is driven at a speed proportional to the engine speed, so that variations in engine speed are directly proportional to variations in the speed of rotation of the shaft 25. A preferred form of driving connection consists in a 45 flexible shaft (not shown) connecting the shaft 25 to the cam shaft of the internal combustion engine.

The rotor assembly 24 includes a rotatable body 29 fixed on the shaft 25 and provided with 50 a plurality of reciprocating pump units generally 55

designated 30. These pump units 30 are duplicates, and while I have shown that eight of these are provided in the body 29, only one will be described in detail. Each of these pump units 30 includes a piston 31 adapted to reciprocate within a radial bore 32 provided in the body 29. A counterbore 33 provides an annular space 34 encircling the upper end of the piston 31. The outer end of this space is closed by the annular flexible diaphragm 35. The diaphragm 35 is positioned at the bottom of a recess 36 formed coaxially of the bore 32 and counterbore 33, and the diaphragm is maintained in position by means of a follower ring 37 and a deformable ring 38. The ring 38 is inserted into the recess 36 and deformed or crimped to maintain it in position. The shape of the ring before such deformation is shown in Figure 9. The ring 38 is provided with a central aperture 39 and a plurality of breather ports 40.

The piston generally designated 31 is provided with a central opening 41 adapted to receive a compression spring 42 normally acting to move the piston 31 outwardly within the bore 32. A cap 43 having a contact surface 44 at its outer end is threadedly mounted on the upper portion of the piston 31 and serves to confine the inner portion of the diaphragm 35 between the washer 45 and the shoulder 46 on the piston 31. The cap 43 is provided with an outer cylindrical surface 47 adapted to reciprocate within the aperture 39 in the retaining ring 38. From the above description it will be understood that the piston 31, cap 43 and washer 45 may reciprocate as a unit within the cylindrical bore 32, flexing the diaphragm 35.

Rotation of the shaft 25 and the body 29 carries the rotatable sleeve 23 around at the same time by reason of the frictional contact between the surfaces 44 on the end caps 43 and the inner surface 48 of the sleeve 23. The sleeve 23 turns within the non-rotary ring 18 on the anti-friction ball elements 22.

Means are provided for shifting the non-rotary ring 18 and the rotary sleeve 23 in a direction transverse to the axis of the rotary shaft 25. The purpose of shifting the ring and sleeve is to develop eccentricity between the rotor assembly 24 and the sleeve 23, so that each pump unit 30 operates as the rotor revolves. As shown in Figure 5 of the drawings, a link 50 is pivotally connected at 51 to the non-rotary ring 18 and is pivotally connected to the lever 52 at 53. A crank pin 54 fixed to the actuating arm 55 is also fixed to the crank arm 56 within the housing 11. A compression spring 51 is provided for the purpose of resiliently urging the crank 56 to move in a clockwise direction as viewed in Figures 5, and hence to contact the inner end of the threaded stop element 58. The stop element 58 may be adjusted to the desired position and fixed by means of the jam nut 59.

A pivot pin 60 serves to connect the crank 56 with the lever 52. A pin 61 at the upper end of the lever 52 connects the lever with a movable member 62 mounted centrally of the control diaphragm 63. This control diaphragm is clamped in position between cooperating flanges 64 and 65 provided on the housing 11 and cap 66 respectively. The cap 66 is shaped to provide a cavity or chamber 67 therewithin on one side of the diaphragm 63 and positioned within this chamber is a compression spring 68. One end of the spring 68 engages the follower element 69 which is secured to the member 62. The other end of

the spring engages a movable seat 70. An adjusting screw 71 threaded through the end wall 72 of the cap 66 is provided in adjusting the compression of the spring 68, and a jam nut 73 is provided to hold the screw 71 in adjusted position. A threaded opening 74 extending through the wall of the cap 66 communicates with the chamber 67. As shown in Figures 1, 2 and 3 a transfer pipe 75 communicates between the opening 74 and the interior of the intake manifold 76 of the engine. The transfer pipe 75 enters the intake manifold at a location downstream from the throttle valve 77.

From the above description it will be understood that vacuum pressure existing in the intake manifold downstream from the throttle valve 77 is communicated to the chamber 67. The resulting reduction in absolute pressure within the chamber 67 enables atmospheric air pressure in the left side of the diaphragm 63 as shown in Figure 5 to move the diaphragm 63 and member 62 to the right against the action of the force of the spring 68. Movement of the member 62 to the right causes the lever 52 to pivot about the pin 60 and hence move the link 50 and lower portion of the ring 18 toward the right. This action reduces the eccentricity of the ring 18 and sleeve 23; hence reduces the stroke of each of the pump units 30.

As shown in Figure 6, each of the pump units 30 is provided with inlet and discharge ports 78 and 79 which are formed within the body 29. These pairs of ports 78 and 79 each meet at a series of common junction ports 80. Four of these ports 80 extend through the end surface 81 on the body 29 and an additional four of these ports 80 extend through the end surface 82. A non-rotary washer 83 is adapted to contact the end face 81, and a similar non-rotary washer 84 is adapted to contact the end face 82. Each of these washers is preferably formed of resilient material, and the faces 82 and 81 are smoothly finished and then lapped to insure a smooth flat surface. Each of the washers is provided with a pair of laterally extending ears 85 adapted to be received in corresponding recesses 86 in the non-rotary port members 87 positioned at opposite ends of the housing 11. The members 87 are substantially duplicates, and accordingly only one need be described. Each of these members 87 is provided with a central opening 88 encircling the shaft 25 and providing clearance therewith.

A counterbore 89 receives the washer 83. Communicating with this counterbore are inlet and discharge ports 90 and 91. These ports communicate with semi-circular grooves 92 and 93 formed in the washer 83. The grooves 92 and 93 do not meet but are separated by relatively short dikes 94. As each of the junction ports 80 revolves it is alternately placed in communication with the grooves 92 and 93, and hence except for the interval when it is passing over the dikes 94 it is in communication with the inlet port 90 or the outlet port 91 provided in the member 87.

Since it is very difficult to obtain a smooth flat end surface on a rotating member which is exactly at right angles to the axis of rotation, there is always the possibility that the surfaces 81 and 82 may be slightly out of square with the axis of the shaft 25. Accordingly, I prefer to employ washers 83 and 84 which are resilient in character, and further to provide resilient mountings for the members 87. Each of the members 87 includes a pair of projections 95 extending outwardly through apertures provided in a flexible

diaphragm 96. Diaphragms 96 are confined between the end member 12 and spacer 14, and between the closure 13 and the housing 11 respectively. Diaphragms 96 function to prevent rotation of the members 87 and also to allow them to oscillate slightly if necessary as the rotor assembly 24 turns in order to maintain optimum sealing characteristics between the surface 81 and the washer 83 and between the surface 82 and the washer 84. A nut 97 is threadedly mounted on each of the projections 95 and serves to compress a sealing washer 98 against the surface of the diaphragm 96. A spring 99 encircles a portion of each of the projections 95 and serves to provide the proper contact pressure between the washers and the sealing surfaces 81 and 82.

Separate cavities 100 and 101 are provided in the end cap 12 for communication with the outlet port 91 and inlet port 90 respectively. Similarly, separate cavities 102 and 103 are provided in the closure 13 for communication with the outlet port 104 and inlet port 105. A passage 106 extending through the end cap 12, spacer 14, housing 11, closure 13 and through the diaphragms 96 and gasket 107 serves to connect the inlet cavities 101 and 103 with the inlet opening 108 at the lower central portion of the housing 11. An inlet pipe 109 as shown in Figures 1, 2 and 3, serves to connect the opening 108 with the fuel tank 110.

The outlet openings 111 and 112 provided in the end cap 12 and closure 13 communicate with the outlet cavities 100 and 102 respectively. Discharge pipes 113 and 114 connected to the openings 111 and 112 respectively are adapted to communicate with the intake manifold. As shown in Figure 1, these discharge pipes 113 and 114 may communicate with the intake manifold at spaced points downstream from the throttle valve 71. As an alternate arrangement the discharge pipes 113 and 114 may enter the manifold at a common point downstream from the throttle valve 71 as shown in Figure 2. As a further example the discharge pipes 113 and 114 may enter the intake manifold at a common point upstream from the throttle valve 71 as shown in Figure 3. The pump assembly 10 as shown in Figures 1, 2 and 3, is illustrated as being in close proximity to the intake manifold, but is contemplated that the pump may be placed at any convenient point, away from the heat of the engine if desired. The pump 10 may be placed above or below the tank 110.

The interior of the housing 11 may be filled with a light oil if desired, and a filler opening 115 is provided for introducing such oil. A plug 121 may be utilized to close the opening 115. The seal between such plug and the opening 115 is not intended to be air tight, however, since it is desired that the interior of the housing 11 be maintained at atmospheric pressure. A seal ring 116 of conventional type may be employed within the end cap 12 to prevent escape of lubricant from the interior of the housing 11 along the shaft 25. Leakage of fuel from the passageways 80 across the sealing surfaces 81 and 82 is prevented by the contact face of the washers 83 and 84, the fuel serving as a lubricant for the faces 81 and 82 to provide an effective seal.

In the normal operation of the device the diaphragm 63 remains in its retracted position as shown in Figure 5, while the engine is idling or operating under substantially no-load conditions, since the vacuum pressure is high at such times. If the engine is speeded up under light

load or no-load conditions, the diaphragm remains substantially in the same position since the vacuum pressure as reflected in the chamber 67 remains high. The engine receives the proper amount of fuel, however, since the speed of rotation of the rotor assembly 24 increases directly with increase in the engine speed. When a load is applied to the engine when it is turning at either high or low speed, the vacuum pressure diminishes, raising the absolute pressure within the chamber 67 and allowing the spring 68 to move the diaphragm 63 to the left. This motion results in pivotal movement of the lever 52 in a counterclockwise direction, hence shifts a ring 18 to the left to increase the pumping stroke of each of the pump units 30. In this way more fuel is delivered when additional load is applied to the engine. Conversely when the load on the engine is lessened the manifold suction pressure increases and the ring 18 is moved to diminish the eccentricity, and hence reduces the stroke of each of the pump units 30.

The control arm 55 is provided for the purpose of securing greater fuel delivery rates from the pump under cold starting conditions. Thus when the engine is cold the control arm 55 may be manually pivoted in a counterclockwise direction as shown in Figure 5 to compress the spring 51 and move the lower end of the lever 52 toward the left. This increases the eccentricity of the ring 18 and sleeve 23, and hence results in a greater rate of flow of fuel to the engine.

It is well known that the optimum fuel-air mixtures at sea level are less efficient at higher altitudes, and it is necessary to reduce the amount of fuel in the mixture to secure proper engine performance at higher altitudes. In accordance with a feature of my invention, I prefer to provide means for automatically limiting the maximum rate of fuel delivery from the metering fuel pump in relation to changes in atmospheric pressure.

As shown in Figure 5 a metallic Sylphon bellows 117 is sealed at both ends containing an inert gas at atmospheric pressure, the gas preferably being one with a low coefficient of temperature expansion. The metallic bellows 117 is preferably mounted within the housing 11 and carried on an adjusting screw 118 provided with a jam nut 119. The adjusting screw is positioned so that at sea level the contact lug 120 on the ring 18 just begins to engage the free end of the bellows 117 when the ring 18 is in idling position; that is, at a very small eccentricity. When the engine operates at elevations above sea level the force exerted by the bellows against the contact lug 120 remains substantially constant for any particular position of the ring 18, while the force exerted by reason of the differential in pressure across the diaphragm 63 is reduced, owing to reduction in pressure on the atmospheric side of the diaphragm 63. The effect of the force exerted by the bellows 117 therefore increases as the atmospheric pressure decreases. Accordingly, at any altitude at which the engine operates the maximum correction occurs at full throttle, and from full throttle the bellows 117 acts on a diminishing scale down to idle position.

It will be understood that various changes in the mounting of the bellows may be made without departing from the spirit of this invention in order that the bellows may be made effective under any given range of movement of the ring 18, as desired. The position of the ring 18 at any given instant is determined by the balance of

forces exerted by the bellows 117 and the link 50. The spring rate or relative stiffness of the bellows 117 is chosen so that it is effective in resisting to the proper degree the resultant force applied by the diaphragm 63 and spring 67.

Having fully described my invention, it is to be understood that I do not wish to be limited to the details herein set forth, but my invention is of the full scope of the appended claims.

I claim:

1. In a fuel pump, the combination of a casing; a rotor within the casing; pump means on the rotor, the rotor having a plane end face provided with ports communicating with said pump means; valve means including a nonrotatable ported washer adapted to contact said end face in sealing relation; a support member for said washer, said member being provided with inlet and outlet passageways communicating with said ported washer; a diaphragm positioned in sealed relationship with respect to said casing; means whereby the support member is carried on the diaphragm; and resilient means acting on the member to maintain pressure between said ported washer and the rotor end surface, the resilient means and diaphragm cooperating to provide a flexible support for said member and washer to accommodate any wobble of said rotor end surface.

2. In a fuel pump, the combination of a casing; a rotor within the casing; pump means on the rotor, the rotor having a plane end face provided with ports communicating with said pump means; valve means including a nonrotatable ported washer adapted to contact said end face in sealing relation; a support member for said washer, said member being provided with inlet and outlet passageways communicating with said ported washer; a diaphragm positioned in sealed relationship with respect to said casing; means

5 whereby the support member is carried on the diaphragm, said means including a plurality of radially spaced projections extending axially through the diaphragm, said member being provided with inlet and outlet passageways communicating with said projections and with said ported washer; a spring engaging each of said projections and cooperating with the diaphragm to provide a flexible support for said member and washer to accommodate any wobble of said rotor end surface, the springs further acting to maintain sealing pressure between said ported washer and the rotor end surface.
